UNITED STATES PATENT OFFICE.

CURTIS B. SMITH, OF PARKERSBURG, WEST VIRGINIA.

EXERCISING APPARATUS.

1,185,015.

Specification of Letters Patent. Patented May 30, 1916.

Application filed August 31, 1915. Serial No. 48,238.

To all whom it may concern:

Be it known that I, CURTIS B. SMITH, a citizen of the United States, residing at Parkersburg, in the county of Wood and State of West Virginia, have invented certain new and useful Improvements in Exercising Apparatus, of which the following is a specification.

My invention relates to improvements in exercising apparatus and has particular reference to such apparatus adapted for use in training boxers.

An important object of the invention is to provide apparatus of the above mentioned character, which will exert a suitable rearward pull upon the boxer, when practising with a punching bag, "shadow boxing" or the like, while leaving the legs and arms free for movement.

A further object of the invention is to provide apparatus of the above mentioned character, having means for indicating, preferably in pounds, the degree of backward pull upon the boxer during the use of the apparatus.

A further object of the invention is to provide apparatus of the above mentioned character, embodying a harness to be placed upon the body of the boxer and having a band or member encircling the solar plexus to exercise and strengthen this part of the body.

A further object of the invention is to provide apparatus of the above mentioned character, which is particularly well adapted for developing leg action, in the boxing.

Other objects and advantages of the invention will be apparent during the course of the following description.

As is well known, in the so called "shadow boxing" it is customary for the trainer to stand behind the boxer and pass his arms around him so that the boxer is held about the waist or stomach. The boxer, while being thus held, practices "shadow boxing." This "shadow boxing" is used generally for leg work and for limbering up the boxer before going into the ring. My apparatus is designed to be used for this purpose, and in connection with a punching bag, and consists broadly of a body encircling member or harness, having connection with an elastic member or spring, which is secured to a stationary object. The punching bag is arranged a suitable distance from the harness so that the boxer, having the harness

on, is forced to place the spring under tension, before he can come close enough to the punching bag to strike it. The spring will yield to the forward lunges, due to arm and leg movements. The apparatus also embodies indicating mechanism, showing the degree of backward pull, under which the boxer is working.

In the accompanying drawings forming a part of this specification and in which like numerals are employed to designate like parts throughout the same, Figure 1 is a perspective view of apparatus embodying my invention, Fig. 2 is an enlarged vertical sectional view through recording mechanism, Fig. 3 is a further enlarged sectional view through a socket member and associated elements included in the recording mechanism, Fig. 4 is a sectional view through the indicator mechanism, showing the wheels and associated elements for operating the hand, Fig. 5 is a perspective view of the body encircling member or harness, and, Fig. 6 is an enlarged fragmentary view of the dial embodied in the indicator.

In the drawings, wherein for the purpose of illustration is shown a preferred embodiment of my invention, the numeral 10 designates a body encircling device or harness, as a whole, embodying a belt 11 adapted to surround the waist of the boxer and cover the solar plexus. This belt has its forward ends adjustably connected by a buckle 12 of any well known or preferred type. The forward ends of the belt 11 preferably carry pads 13 which may be formed of felt or other suitable material. Attached to the rear portion of the belt 11 are shoulder straps 14, which cross, and are adjustably connected with the forward ends of the belt 11 by buckles 15 or the like. The belt 11 has a loop or flap 16 secured to the rear portion thereof for receiving a ring 17, for a purpose to be described.

The numeral 18 designates a nonextensible flexible element, which may be a section of wire, cord or the like. Secured to the forward end of this flexible element is a hook 19 adapted to have detachable engagement with the ring 17. A similar hook 20 is secured to the opposite end of the element 18.

The numeral 21 designates an attaching disk or member, to be secured to a wall or other suitable support, by means of screws 110 or the like. This disk carries a horizontal sleeve 22, having its outer end interiorly

screw-threaded, as shown at 23, for receiving a sleeve-extension 24, as shown. Attached to the sleeve 22 adjacent the disk 21 is an interior bolt 25, receiving thereon the hooked ends of retractile coil springs 26 and 27, arranged one within the other, as shown. The inner spring 27 is much shorter than the outer spring and extends only for a short distance beyond the sleeve-extension 24, as clearly illustrated in Fig. 2. The outer spring 26 has detachable connection with the hook 20, as shown. Instead of spiral springs 26 and 27, it is obvious that other elastic means may be used, such as a coil spring, rubber, or the like.

Connected with the sleeve 22 in a preferably vertical tube 28, to the upper end of which is secured a casing 29 of an indicator. This indicator is provided with a dial 30, having graduations 31, preferably indicating the number of pounds pull upon the spring or springs 26 and 27. Traveling in proximity to the scale 31 is a pointer 32, rigidly mounted upon a rotatable shaft 33. This rotatable shaft, as more clearly shown in Fig. 4, carries a sprocket wheel 34, rigidly connected therewith. The sprocket wheel 34 is turned by a sprocket chain 35, engaging a sprocket wheel 36, carried by a shaft 37. Connected with the upper end of the chain 35 is a flexible element 38, such as a strip of leather, attached to and adapted to be wound upon a flanged pulley 39, rigidly mounted upon a rotatable shaft 40. The shaft is turned in a direction to wind the leather upon the pulley by a spring 41, connected with the shaft and the casing 29, as shown at 42. Connected with the lower end of the sprocket chain 35 is a flexible element 43, such as a section of wire. This flexible element extends into the casing 22 and is passed about a pulley 44, carried by a horizontal shaft 45, attached to the sleeve 22. The cable 43 extends through the inner spring 27, and is attached to a transverse member or handle 46, which is passed between the turns of the inner and outer coil springs 26 and 27, as shown.

The numeral 47 designates a punching bag or other exercising device.

In the use of the apparatus, the disk 21 is secured to a wall or other support and the apparatus assumes substantially the position shown in Fig. 1. The harness is placed upon the boxer with the belt 11 extending about the solar plexus while the straps 14 extend over the shoulders. The punching bag or other exercising device is arranged a substantial distance from the harness so that the boxer, in order to come in striking reach of the punching bag, places the spring or springs 26 and 27 under tension. The degree of tension of these springs or the back pull upon the boxes, will effect a corresponding movement of the pointer

32, which travels in proximity to the scale 31, indicating such pull in pounds.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In an exercising apparatus of the character described, a body receiving harness, an elastic member secured to the harness, means for connecting the elastic member with a support, and a punching bag arranged a substantial distance from the harness so that the boxer is compelled to place the elastic member under tension to come within striking distance of the punching bag.

2. In an exercising apparatus of the character described, a body receiving harness, an elastic member secured to the harness, means for connecting the elastic member with a support, an indicating mechanism embodying a scale and pointer coöperating therewith and having connection with the elastic member to be moved thereby, and a punching bag arranged a substantial distance from the body receiving harness so that the boxer is compelled to place the elastic member under tension to come within striking distance of the punching bag.

3. In an exercising apparatus of the character described, a body receiving harness embodying a belt surrounding the body of the boxer and covering the solar plexus, an elastic member secured to the rear portion of the harness and adapted for connection with a support, and a punching bag arranged a substantial distance from the harness so that the boxer is compelled to place the elastic member under tension to come within striking distance of the punching bag.

4. In an exercising apparatus of the character described, a harness for receiving the body of a boxer, of a retractile coil spring, means for connecting the coil spring with a fixed support, a flexible element connecting the opposite end of the coil spring with the harness; in combination with a punching bag arranged a substantial distance from the harness so that the boxer is compelled to place the coil spring under tension to come within striking distance of the punching bag.

5. In an exercising apparatus of the character described, a harness for receiving the body of a boxer, a retractile coil spring adapted to be connected with a stationary support, means connecting the coil spring and harness, and an indicating mechanism embodying a scale and pointer coöperating

therewith and having connection with the coil spring to be moved thereby.

6. In an exercising apparatus of the character described, a belt for surrounding the body of the boxer and covering the solar plexus, means for holding the belt in place upon the boxer, an elastic member adapted to be secured to a suitable support, and means connecting the rear portion of the belt and elastic member.

7. In an exercising apparatus of the character described, an attaching element, a body encircling member, a coil spring having connection with the attaching element and body encircling member, a flexible element extending into the coil spring and connected therewith, a dial having a scale, a pointer to travel

in proximity to the scale, and means to operate the pointer connected with the flexible element.

8. In an exercising apparatus of the character described, a belt for surrounding the body of the boxer and covering the solar plexus, pads secured to the forward side of the belt to engage the solar plexus, an elastic member secured to the rear side of the belt, and means for connecting the elastic member with a support.

In testimony whereof I affix my signature in presence of two witnesses.

CURTIS B. SMITH.
